UNITED STATES PATENT OFFICE.

DURBIN GRUPE, OF DAVENPORT, IOWA.

ROTARY DRIER.

SPECIFICATION forming part of Letters Patent No. 738,106, dated September 1, 1903.

Application filed May 20, 1903. Serial No. 158,034. (No model.)

To all whom it may concern:

Be it known that I, DURBIN GRUPE, a citizen of the United States, and a resident of Davenport, in the county of Scott and State of Iowa, have invented certain new and useful Improvements in Rotary Driers, of which the following is a clear, full, and exact specification, reference being had to the accompanying drawings.

10 My invention relates to that class of rotary driers employed in breweries and glucose factories and other places to dry raw or spent materials used or produced in such institutions and consisting principally of long cylinders traversed longitudinally by steam-flues, into which cylinders the material to be dried is fed at one end and discharged at the opposite end. This is the class of driers to which Letters Patent of the United States No. 20 659,299, issued to me October 9, 1900, refer. Difficulty has been experienced in maintaining the operative condition of such driers, because the expansion and contraction of the flues has a tendency to cause the connections 25 at their ends to work loose, there being too great a weight of the movable chamber and flues to allow the movable chamber to move readily, and because the unequal expansion of the different flues tends to make the movable chamber bind; also, to cause the flues to buckle or to crack. Difficulty has also been experienced from the location of the trap without the cylinder, it interfering with nesting the cylinders, occupying needed space, and 35 weakening the cylinders.

The object of my present invention is to obviate these difficulties by providing for the free and unhampered movement of the movable ends of the flues upon contraction or expansion, either singly or in groups, and by an improved drain-trap.

In the drawings, Figure 1 represents a side view of my invention. Fig. 2 is a longitudinal central section thereof. Fig. 3 is an end view of the entrance end, showing a part of the steam-chambers *a*, some of the caps *M* being omitted. Fig. 4 is a detail showing the location of the water-trap within the rear steam-chamber *X*. Fig. 4^a is a perspective 45 view of the drain-trap. Fig. 5 is an end detail of the steam-chambers *L*, showing the

caps *M*, nuts *N*, and air-vent *Q*, the dotted lines showing the partitions of the steam-chambers. Fig. 6 is a side detail of the steam-chambers *L* in section on the dotted line 2 of 55 Fig. 5. Fig. 7 is a side elevation showing the inclination of the cylindrical shell.

In the drawings similar letters refer to similar parts in the various views.

Fig. 1 represents the cylindrical shell *A* of 60 a rotary drier, which is revolved by means of suitable gearing *B'*, engaging an annular gear *B*, secured to the cylindrical shell *A*, preferably by one of the bearing-rings *C*. There are two or more of these bearing-rings located 65 at suitable distances apart. These rings travel upon nests of idle rollers *F*. Placed longitudinally in the cylindrical shell, arranged in such a manner as to leave a central area unoccupied by the same, are a number 70 of flues *E*. One end of each flue is secured in any suitable manner in one head *b* of the chamber *X*, immovably secured in place at one end of the cylindrical shell, preferably the discharge end. This chamber *X* is composed of two corresponding circular plates or 75 heads *b* and *b'*, secured to the cylindrical shell at a suitable distance apart, a portion of the cylindrical shell *A* forming the circumferential walls of the chamber. The opposite ends 80 of the flues are suitably secured, either singly, in pairs, or in groups of three or more, in chambers *L*, consisting of an inner head, an outer head, and connecting walls. These chambers may be cast in one piece or built up. When 85 the inner connecting walls are used, as shown in Fig. 6, they are provided with openings *o* to allow the free passage of steam to and from all parts of the chamber. The outer head is provided with as many openings as there are 90 flues entering the chamber. These openings are made slightly larger than the flues to permit the introduction of tools and are provided with caps *M*, secured in place by dogs *R* and bolts *S*, each dog *R* being provided with a slot 95 to receive the head of the bolt and prevent its turning. The caps *M* are provided with gaskets *T* to make them steam-tight. When necessary, provision is made against an accumulation of air in these chambers by suitably attaching thereto automatic air-vents of any 100 standard pattern, no claim being made here-

in for any particular form of air-vent, or the caps M may be fitted with automatic air-vents Q.

Near the movable end of the flues a supporting-plate f is fitted within the cylindrical shell, having holes slightly larger than the flues through which the flues pass, the holes being enough larger than the flues to allow the free longitudinal movement of the flues therein. The central portion of the plate f is cut away to permit the introduction of the feed within the drier.

My drain-trap consists of an open segmental chamber K, formed upon the inner side of the cylindrical shell between the two heads of the chamber X. The forward end of this chamber K is open. The rear end is fitted with a radial pipe J, which is bent at right angles at the center of the cylindrical shell and passes out within and through the entry-pipe H. This drain-pipe is suitably packed where it leaves the steam-entry pipe H, so as to allow its free revolution. A suitably-packed steam-entry pipe H enters the center of the outer head b' of the steam-chamber X in such manner that the steam-supply is not interfered with by the revolution of the cylindrical shell.

The cylindrical shell is provided with holes V through the shell near the steam-chamber X, which allow the dried materials to pass out into any suitable receptacle. Whenever the length of the flues requires, intermediate supporting-plates G may be disposed in any manner which does not interfere with the progress of the material through the drier.

In operation steam is introduced through the pipe H into the chamber X and passes thence into the flues E and the chambers L. When the chambers L are fitted to receive only a single flue, or otherwise when desired, air is allowed to escape through the automatic air-vents Q, which may be of any approved pattern. When the flues are thus heated to the desired temperature, the material to be dried is fed into the central opening of the supporting-plate f by a suitable conveyer. The entrance end of the drier is mounted higher than the opposite end, so that when the cylindrical shell revolves the feed or material is advanced by gravity toward the discharge end and passes out through the discharge-holes. This advance of the material may be facilitated by longitudinally-disposed ribs secured to the inner side of the shell and extending substantially the length of the flues.

The water from condensation collects by gravity in the chamber X and with each revolution of the cylinder is caught in the open chamber K and passes thence into the drain-pipe and out through a suitable trap.

What I claim as new, and desire to secure by Letters Patent, is—

65 1. A rotary drier comprising a cylindrical shell having a discharge-opening, inner supporting-plate, and outer plate providing a

steam-chamber at one end of the shell, a steam-supply pipe connected with the steam-chamber, an outer supporting-plate having a central opening and located at the other end of the shell, steam-flues having their inner ends fixed in the inner supporting-plate and extending into the steam-chamber and their outer ends movably mounted in the outer supporting-plate and extending beyond the same, and small steam-chambers having inner openings in which the outer ends of the flues are fixed, and outer openings opposite to the inner openings, and removable caps secured to the outer openings of the small steam-chambers.

2. A rotary drier comprising a cylindrical shell having a discharge-opening, inner supporting-plate, and outer plate providing a steam-chamber at one end of the shell, a steam-supply pipe connected with the steam-chamber, an outer supporting-plate having a central opening and located at the other end of the shell, steam-flues having their inner ends fixed in the inner supporting-plate and extending into the steam-chamber, and their outer ends movably mounted in the outer supporting-plate and extending beyond the same, and small steam-chambers connecting the flues in pairs and having inner openings in which the outer ends of the flues are fixed, and outer openings opposite to the inner openings, and removable caps secured to the outer openings of the small steam-chambers.

3. A rotary drier comprising a cylindrical shell having a discharge-opening, inner supporting-plate, and outer plate providing a steam-chamber at one end of the shell, a steam-supply pipe connected with the steam-chamber, an outer supporting-plate having a central opening and located at the other end of the shell, steam-flues having their inner ends fixed in the inner supporting-plate and extending into the steam-chamber, and their outer ends movably mounted in the outer supporting-plate and extending beyond the same, and small steam-chambers connecting the flues in groups of three and formed with walls provided with connecting openings and having inner openings in which the outer ends of the flues are fixed, and outer openings opposite to the inner openings, and removable caps secured to the outer openings of the small steam-chambers.

4. A rotary drier comprising a cylindrical shell having a discharge-opening, inner supporting-plate, and outer plate providing a steam-chamber at one end of the shell, a steam-supply pipe connected with the steam-chamber, an outer supporting-plate having a central opening and located at the other end of the shell, steam-flues having their inner ends fixed in the inner supporting-plate and extending into the steam-chamber, and their outer ends movably mounted in the outer supporting-plate and extending beyond the same, and small steam-chambers having inner openings in which the outer ends of the flues

are fixed, and outer openings opposite to the inner openings, and removable caps having slotted dogs and bolts whereby the caps are secured to the outer openings of the small steam-chambers.

5. A rotary drier comprising a cylindrical shell having a discharge-opening, inner supporting-plate, and outer plate providing a steam-chamber at one end of the shell, a steam-supply pipe connected with the steam-chamber, an outer supporting-plate having a central opening and located at the other end of the shell, steam-flues having their inner ends fixed in the inner supporting-plate and 10 extending into the steam-chamber, and their 15

outer ends movably mounted in the outer supporting-plate and extending beyond the same, and small steam-chambers having inner openings in which the outer ends of the flues are fixed, and a drain-trap consisting of a segmental chamber secured to the shell within the steam-chamber having one end open and the other end closed and a pipe extending from the closed end of the chamber to the center of the steam-chamber and axially through the 20 steam-pipe.
